ABSTRACT OF THE DISCLOSURE

A washable bedpan cover which is wholly nonmetallic and is designed for easy insertion and removal of a bedpan, includes a flexible, yielding cushion seat of horseshoe shape having side walls attached to it at the outer edge, and a base which slips under the bedpan, and a semiflexible flap attached to the cushion underneath and along its inner edge. This flap can be progressively turned downward so that it does not hinder the mounting of a bedpan therein, and can then be turned outward and upward so as to clasp the inner margin of the bedpan and thus be held securely in place.

This application is a continuation-in-part of my pending application Ser. No. 447,138, filed Apr. 12, 1965.

BACKGROUND ART

A bedpan used without any cushioning seat pad between the pan and the patient's body is a source of discomfort and distress to the patient, particularly one whose body is thin and wasted.

Many proposals of cushioned bedpan covers have been made, but none of the resulting pads has been eminently satisfactory and none has been widely adopted or used. Some undesirable features have been the presence of various metallic parts such as hooks and clamps, valve stems, etc.

DETAILS OF THE INVENTION

My invention provides a cushioned bedpan cover or envelope which is of simple construction, is made entirely of flexible, washable and noncorrodible materials, having no metal parts, and is comfortable and convenient to use, being easy to mount and remove.

My improved cushioned bedpan envelope comprises essentially a cushion seat body and a bottom panel and side walls together forming a pocket into which a bedpan can be inserted, and flexible retaining flap means attached to the under side of the seat body so as to clasp the inner edge of the bedpan and thus prevent displacement of the seat in use.

The invention will be understood from the following detailed description and the appended drawing, in which:

FIG. 1 is a top plan view of my bedpan envelope;
FIG. 2 is a side view of the envelope;
FIG. 3 is a bottom plan view of the envelope;
FIG. 4 is a cross-section on the line 4—4 of FIG. 1;
FIG. 5 is a plan view of a one-piece retaining flap;
FIG. 6 is a plan view of a pair of separate retaining flaps;

FIG. 7 is a detailed cross-section of the retaining flap attached to the cushion and put in the turned-down position; and

FIG. 8 is a side view of an envelope having a different sidewall contour.

As shown in the drawing, my cushioned bedpan envelope, indicated generally at 10, includes a seat pad 11 made of nonabsorbent, resilient, cellular or expanded rubbery material and conforming in its configuration to the horseshoe-shaped seat portion of a conventional bedpan. A base, or bottom panel, 12, formed of nonabsorbent

2

sheet material, extends under at least the rearward half of the seat pad, and its upwardly turned outer margin is joined to the side and rear outer edges of the seat pad. The seat pad and the base thus form an open-ended pocket into which a bedpan can easily be inserted.

Attached to the under side of the inner, curved rim 13 of the seat pad there is a flap or retaining strip 14 which extends, underneath the cushion, part way toward the outer rim thereof. The purpose of the flap 14 is to clasp the underside of the seat portion of the bedpan along its inner margin. If so desired, a narrow spacing strip 15 is inserted between the inner border of the flap 14 and the inner rim of the cushion, thus holding the cushion securely in place and preventing its displacement by movement of the patient. The flap 14 is made of flexible, but at the same time somewhat stiff, rubbery or plastic material—only stiff enough so that it will not yield and permit displacement of the cover from the bedpan. The flap 14 is cut or molded in a slightly dish-shaped, upwardly concave contour, as shown in FIG. 4, conforming to the slope of the seat portion of a bedpan. When the cushioned cover is in use, the outer edge of the flap 14 lies close to the underside of the bedpan seat. When the cover is to be placed over a bedpan or removed, the flap 14 may be turned down all around, as indicated in FIG. 7, to permit insertion or removal of the bedpan.

The turning down of the flap is readily accomplished by applying a progressive bending or twisting pressure with the hands, starting at the rear, median portion of the flap and progressing along either side to the open ends, or starting at one end and progressing along the flap to the other end. With the flap thus entirely turned down, the seat cover is readily mounted on the bedpan, the turned-down flap clearing the inner margin of the seat, and extending below the rim. The flap is then progressively turned upward by applying pressure in the opposite direction to that by which it was turned down. The flap is thus forced into the turned-up, or clasping, position. The semirigid, semiflexible character of the flap permits this progressive, wave-like twisting to be performed easily. The down-turning is also facilitated by the soft, yielding character of the cushion material, which permits the cushion material at its juncture with the flap 14 to be depressed by the turning of the flap, as clearly shown in FIG. 7. Any distortion of the flap while it is being turned from one position to the other is accommodated by the yielding nature of the seat material.

It will sometimes be convenient to use as the retaining means, in place of the one-piece strip 14, a pair of separate flaps 16, 16, as shown in FIG. 6, extending rearwardly from the forward ends of the seat pad but not extending around the rearward part of the seat pad.

In a slight variant from the shape of sidewall shown in FIG. 2, I may use a sidewall of which the forward ends 17 are tapered and extend upwardly and forwardly to the front extremities of the seat pad, as shown in FIG. 8. By this construction the seat pad is held more securely in place during use.

Suitable materials of which to make the seat pad include, but are not limited to, cellular or expanded polyurethane (commonly called "poly foam"), and cellular or expanded rubber, either natural or synthetic, and the like.

The base and sidewalls 12, and likewise the flaps 14 or 16, and the spacer strips 15 if used, may be made variously of flexible sheet plastic materials of suitable thickness and stiffness such as polyurethane, plasticized polyvinyl chloride, and the like, or of rubber, or textile fabric impregnated or coated with rubber or plastic so as to be nonabsorbent and easily cleaned.

The parts of which the cushioned envelope is constructed may be joined together in various ways well

known in the art, as by the use of adhesive cements or adhesive strips, or by fusion or heat-sealing techniques, vulcanization, etc.

If the exposed surfaces of the expanded seat cushion material are inherently porous, they may be provided with a sealing coat, layer, or skin which is impermeable to liquids, in ways which are also well known to the art. For example, the expanded material may have an integral, nonexpanded, impermeable outer cover or skin formed thereon before or during the expanding operation; or it may be sheathed in an impermeable envelope of thin sheet material within which the expanded material is sealed by joining mating edges of the envelope. Another convenient method is to apply a sealing coat by spraying onto the surface of the cushion material a solution or dispersion of rubber or plastic sealing material to form an impervious layer.

It may sometimes be desirable to insert a small gore 18 of elastic material, such as a piece of stretchable rubber sheet or rubber-coated elastic webbing, in the forward edge of the base 12, when the latter has been made of a non-stretchable material and it is desired to have the base extend forward past the widest part of the seat, as shown in FIG. 3. In this way insertion and removal of a bedpan are facilitated particularly when there is a snug fit.

In using the embodiment of my invention shown in FIGS. 1 and 3, the bedpan cover is drawn first over the rear portion of the bedpan and is then drawn forward to cover the bedpan.

In another embodiment of my invention the rear wall of the base is omitted except for a strip of it just below the rear edge of the cushion, or the rear wall may be slit along a line where it becomes the bottom panel and paralleling the juncture of the rear wall and the cushion, to form a pendant flap across the rear. In these and other ways a rear opening is created through which a bedpan can be inserted and removed. In such case the forward ends of the retaining strip extend to the front extremity of the seat body, and the transverse edges of said forward ends of the strip means can be sealed to the seat body, thus providing a stop which positions the bedpan within the cover. If desired, a strap or straps may be provided extending across the rear opening of the cover either vertically or horizontally or both, to keep the bedpan from sliding out of the cover. Such straps may, for example, be formed of rubber or plastic, one end being sealed to or integral with the cover material and the free end having a hole or a socket and there being a rubber or

plastic boss adhered to the cover material over which the free end of the strap may be pressed to secure it.

In all embodiments of my invention, concave depressions may be formed in the underside of the seat body to act as suction cups to aid in holding the cushion on the pan secure from slipping off. Many other changes and modifications may be made in my invention within the scope of the appended claims.

I claim:

- 10 1. A bedpan cover comprising a resilient, impermeable cushion seat body of cellular or expanded rubbery material, having a central opening and being slightly dished or upwardly concave in contour, a flexible base having side walls joined to the periphery of the seat body, said seat 15 body and base constituting a pocket for reception of a bedpan, and flexible flap means extending under the seat body and secured to and underlying at least the lateral portions of the inner margin of the seat body, said flap being adapted to assume either of two positions, in one 20 of which positions the flap is turned upward so as to conform closely to the dished margin of the seat body and is thus adapted to clasp the inner margin of a bedpan inserted in said cover, and in the other of which positions the flap is turned down and in this position permits ready 25 insertion or removal of a bedpan, the said flap being convertible from one of said positions to the other by hand flexing pressure applied progressively along the length of the flap.
2. A bedpan cover according to claim 1 wherein the exposed faces of said seat body have a surface layer applied thereto which is impenetrable to liquids.
3. A bedpan cover according to claim 1 wherein the retaining flap means underlies the seat body along the entire inner margin thereof.
- 35 4. A bedpan cover according to claim 1 wherein the retaining flap means comprises two separate flaps underlying the lateral inner margins of the seat body.
